[57] **CLAIM**

The ornamental design for a cover for drink dispensing unit, as shown and described.

DESCRIPTION

FIG. 1 is a front elevational view of a cover for a drink dispensing unit showing my new design;

FIG. 2 is a side elevational view thereof, the opposite side being a mirror image;

FIG. 3 is a top plan view of FIG. 1;

FIG. 4 is a bottom plan view of FIG. 1; and,

FIG. 5 is a top front perspective view thereof.

The broken line showing of a drink dispensing unit in FIG. 5 is for illustrative purposes only and forms no part of the claimed design.
